EX

OR D 16,161

H. FINCK.

RUG.

No 16,161.

Patented July 14, 1885.

UNITED STATES PATENT OFFICE.

HENRY FINCK, OF NEW YORK, N. Y., ASSIGNOR TO JOHN BROMLEY & SONS,
OF PHILADELPHIA, PENNSYLVANIA.

DESIGN FOR A RUG.

SPECIFICATION forming part of Design No. 16,161, dated July 14, 1885.

Application filed June 1, 1885. Term of patent 3½ years.

To all whom it may concern:

Be it known that I, HENRY FINCK, a citizen of the United States, residing at New York, in the State of New York, have invented and produced a new and original Design for a Rug; and I do hereby declare that the photographic print accompanying this specification conveys to any one skilled in the art a clear understanding of the same, and is sufficient to enable such person to use my invention.

The leading feature of my design consists in a triple-panel center. The middle panel is ornamented by a series of uniform figures of a peculiar design, as shown, and a narrow cross-border at each end dividing the center from the end panels. A wide border is shown at top and bottom of the middle panel. The end panel on the right hand is ornamented by an Egyptian scene showing foliated ornamentation and a representation of a mosque

or Mohammedan temple, and sky in the background. The end panel on the left hand is ornamented with an Egyptian scene showing foliated ornamentation, a column with its capital in ruins, palm-date trees, and a sky in the background, the whole surrounded by a narrow border, as shown in the photographic print accompanying this specification.

What I claim as my invention is—

The design for a rug, consisting of a triple-panel center, the center panel ornamented by a series of uniform figures, the end panels represented as showing Egyptian scenes—one a temple, the other a column—with foliated ornamentation and borders, the whole as shown and described.

HENRY FINCK.

Witnesses:

GEO. FINCK,
J. M. HELPENSTEIN.
